UNITED STATES PATENT OFFICE.

HOMER E. SHEPARD, OF ROCHESTER, NEW YORK, ASSIGNOR, BY DIRECT AND MESNE ASSIGNMENTS, TO DANIEL B. SUTER, OF ROCHESTER, NEW YORK.

EXPLOSIVE ENGINE.

1,427,555.

Specification of Letters Patent. Patented Aug. 29, 1922.

Application filed March 3, 1921. Serial No. 449,522.

To all whom it may concern:

Be it known that I, HOMER E. SHEPARD, a citizen of the United States, and resident of Rochester, in the county of Monroe and 5 State of New York, have invented certain new and useful Improvements in Explosive Engines, of which the following is a specification.

The present invention relates to explosive engines and more particularly to the connection between the pistons and the crank shaft, this invention being an improvement on the construction shown in my application for a patent filed November 1, 1920, Serial 15 No. 420,899. An object of this invention is to provide a construction by which the results secured in the before mentioned application may be obtained through the employment of a crank shaft formed in a unitary structure rather than in sections, as in 20 my before mentioned application.

To this and other ends the invention consists of certain parts and combinations of parts, all of which will be hereinafter described, the novel features being pointed out 25 in the appended claims.

In the drawings:

Fig. 1 is a fragmentary view partially in section showing two pitman or piston rods 30 connected to the crank shaft;

Fig. 2 is a vertical section on the line 2—2, Fig. 1 through one of the cylinders showing the manner in which a piston or pitman rod connects with the crank shaft;

35 Figs. 3 and 4 are detail views at right angles to each other of the bearing piece which forms the bearing for the rock shaft and the rotary member;

Fig. 5 is a view of the upper bearing member for the rock shaft;

Fig. 6 is a fragmentary sectional view on the line 6—6, Fig. 1;

Fig. 7 is a detail view of one of the parts of the rotary member;

45 Fig. 8 is a side view of the part shown in Fig. 7;

Fig. 9 is a side view of another one of the parts forming the rotary member;

Fig. 10 is a fragmentary section on the 50 line 10—10, Fig. 1, through the rotary member; and

Fig. 11 is a detail view of the bearing block illustrated in Fig. 10.

Referring more particularly to the drawings, 1 indicates a cylinder in which oper-

ates a piston 2, a crank casing 3 being provided at the lower part of the cylinder for containing the crank shaft and the connections between the latter and the different pistons of the engine. Within the crank 60 casing 3 are arranged shelves or ledges 5 which support the spaced bearing pieces 6, these bearing pieces being secured by bolts 7 to the shelves 5. Furthermore, the bearing pieces are each provided with a transverse segmental groove 8 in which the bearing portion 4^a of the crank shaft 4 turns, a removable bearing piece 9 through bolts 10 securing the crank shaft to the bearing pieces 6. It will be noted that the crank 70 shaft is a unitary structure, that is, its crank portions 4^a are rigid with the bearing portions 4^b. The crank shaft has its crank portions 4^a operating between the bearing plates 6 and a fly wheel 4^c is arranged thereon so 75 that a uniform movement of the crank shaft is obtained.

The pistons 2, in this instance, are each connected by pitmen or piston rods 11 with rotary members 16 which turn about an axis 80 parallel with, but eccentric to the turning axis of the crank shaft, the pitmen each having, in this instance, a pivotal connection as at 12 with its piston and also being mounted to turn on a rotary member about 85 an axis which is eccentric to the axis of turning of such rotary member.

In this instance, each rotary member embodies a disk or bearing block 13 which is surrounded by a split ring 14 rigid with 90 one of the pitmen 11, anti-friction bearings 15 preferably in the form of rollers, being interposed between the split bearing ring and the bearing disk or member 13. The disk or bearing block 13 is held between two 95 substantially disk shaped portions 16 by bolts 17, the disk shaped portions projecting beyond the bearing portion 13 to provide flanges operating on opposite sides of the split ring 14. Each disk portion 16 is preferably mounted on one section 18 of a split ring, the other half 19 of said ring being secured to the half 18 by bolts 20. This split ring 18—19, which with the disk 16 and the bearing 13 form, in this instance, 100 a rotary member, turns about an axis which is out of line with or eccentric to the axis of turning of the crank shaft 4. In this instance, the two split rings of each rotary member turn on anti-friction rollers 21^a upon 110

a pair of annular bearing members 21 which surround the crank shaft and are situated on opposite sides of a crank portion 4^b of the crank shaft. Each bearing, in this instance, is formed integrally with a plate 6, the bearings 21 of each pair being on two different but proximate plates 6.

The connection between each rotary member and a crank portion on the crank shaft 10 is established, in this instance, by providing the bearing block 13 with a transversely extending guideway 22 on which operates a slide block 23. This slide block has a bearing 24 in which rocks the crank portion 4^a 15 of the crank shaft.

In the operation of the engine, each piston 2 on its out stroke exerts its force on the crank shaft 4 at a time when the crank portion 4^a is situated nearest the inner end of 20 the guideway 22, so that the rotary member increases the effective length of the crank portion, whereby is obtained a greater leverage and greater force acting upon the crank shaft on the out stroke of the piston. On 25 the in stroke of the piston, the block 23 moves toward the outer end of the guideway 22 and in this way the force required for moving the piston inwardly is reduced and due to the fact that the crank portion 30 of the shaft acts on the rotary member at a point at a greater distance from the center of the rotary member, thus reducing the leverage on the in stroke. It therefore follows that a greater amount of power can 35 be obtained from the engine. This result, which forms the basis of my pending application herebefore mentioned, is accomplished in this invention by the employment of a single crank shaft. The construction 40 for securing this result is strong and durable and is simple and inexpensive to manufacture.

What I claim as my invention and desire to secure by Letters Patent is:

45 1. An explosive engine comprising a cylinder, a piston, a piston rod, a crank shaft, and a rotary member mounted to turn about an axis parallel with but out of alignment with the axis of turning of the crank shaft, 50 said rotary member having the piston rod turning thereon about an axis out of alignment with the axis of turning of said rotary member and said rotary member also having a sliding connection with the crank 55 shaft at a point out of alignment with the axis of turning of said crank shaft.

2. An explosive engine comprising a cylinder, a piston operating in the cylinder, a crank shaft formed in a unitary structure, 60 two bearings arranged eccentrically with relation to the axis of the crank shaft on opposite sides of each crank portion of the crank shaft, rotary members, each turning on two of said bearings about axes parallel 65 with but out of line with the axis of turn-

ing of the crank shaft, each rotary member being connected to one of the pistons, and being connected also with the adjacent crank portion of the crank shaft, so that a greater leverage action on the crank shaft 70 is obtained on the out stroke of the piston than on the in stroke.

3. An explosive engine comprising a cylinder, a piston operating therein, a crank shaft having a crank portion, two bearings 75 arranged eccentrically with relation to the axis of the crank shaft on opposite sides of such crank portion of the crank shaft, and a rotary member mounted to turn on both bearings about an axis parallel with but out 80 of alignment with the axis of turning of the crank shaft, said rotary member acting as a crank pin and having the piston rod turning thereon, and having a sliding connection with the crank portion of the crank 85 shaft, so that a greater leverage action on the crank shaft is obtained on the out stroke of the piston than on the in stroke.

4. An explosive engine comprising a cylinder, a piston operating therein, a crank 90 shaft having a crank portion, a pair of bearings for the crank portion having the members thereof arranged eccentrically with reference to the axis of the crank shaft on opposite sides of such crank portion, a 95 rotary member mounted to turn on both bearings about an axis parallel with but out of alignment with the axis of turning of the crank shaft, said rotary member acting as a crank pin and having a piston 100 rod mounted to turn thereon, and being provided with a guideway, and a block movable on said guideway and having the crank portion mounted to rock therein.

5. An explosive engine comprising a plurality of cylinders, pistons operating therein, piston rods pivotally connected to the cylinders, a crank shaft formed in a unitary structure, bearings surrounding said crank shaft and arranged eccentrically 110 with reference to the axis of the crank shaft in pairs on opposite sides of the crank portions of said shaft, rotary members, each mounted to turn on a pair of said bearings about axes parallel with but out of alignment with the axis of turning of the crank shaft, the rotary members acting as a crank pin and having the piston rods mounted to turn thereon between the members of its pair of bearings, and also having sliding 115 connection with one of the crank portions of the crank shaft at a point eccentric to the axis of turning of the rotary member so that a greater leverage action on the crank shaft is obtained on the out stroke of a 120 piston than on the in stroke.

6. An explosive engine comprising a plurality of cylinders, pistons operating therein, piston rods pivotally connected to the pistons, a plurality of spaced bearing plates, 130

- a unitary crank shaft mounted to turn on said plates and having crank portions operating between the plates, substantially ring shaped bearings mounted on the plates in 5 pairs about the crank shaft with the members of each pair arranged on opposite sides of a crank portion, rotary members, each mounted to turn upon a pair of bearings about an axis parallel with but out of alignment with the axis of turning of the crank shaft, each of said rotary members acting as a crank pin and having one of the pitmen rods turning thereon about an axis eccentric to the axis of turning of the rotary member, 10 the plane of operation of the pitman rod being between the two bearings of the rotary member, and a block mounted to slide upon each rotary member and having one of the crank portions of the crank shaft 15 mounted to rock therein.
- 20
7. In an explosive engine, the combination with a plurality of cylinders, pistons operating therein, piston rods pivotally connected to the pistons, a crank shaft formed in a unitary structure, and bearings surrounding said crank shaft and arranged in pairs, the members of each of which are situated on opposite sides of one of the crank portions, of rotary members, each embodying two split rings turning upon the 25 two members of a pair of bearings, two substantially disk shaped plates carried by said split rings, and a bearing block arranged between said disk shaped plates and formed with a guideway, the piston rods being 30 mounted to turn on the bearing block, and slides each mounted to operate in the guideway of a bearing block and having one of the crank portions of the crank shaft 35 mounted to rock therein.

7. In an explosive engine, the combination
